UNITED STATES PATENT OFFICE.

JOHN F. WINTER, OF YOUNGSTOWN, OHIO.

DEVICE FOR STRAIGHTENING WHEELS.

Application filed November 14, 1925. Serial No. 69,077.

My invention pertains to devices designed primarily for straightening disk wheels, the object being to provide an effective device for removing the dents and displacements 5 from the disk of an automobile wheel, and truing the same up generally.

As is well known, the disk wheel for automobiles is rapidly gaining in popularity, and an efficient device of this character has 10 come to be a really indispensable factor or unit in every well equipped garage and automobile repair shop.

In the drawings accompanying the application, Figure 1 is a top plan view, with the 15 wheel in position to be operated upon; Figure 2 is a side elevation, also showing the wheel in position; Figure 3 is an end view; and Figure 4 is a detail sectional view on line 4—4 Figure 2, illustrating the mounting 20 of one of the operating screws.

1—1 represent the posts of the frame-work, and 2 the bracings or reinforcements of the same.

Rigidly secured to the upper portion of 25 the posts are the oppositely disposed transverse bars 3—3, which also form a part of the frame-work, as well as serving to support the guide-ways described in the next paragraph.

30 Rigidly secured to the transverse bars 3—3, one above and the other below, and adjacent what may be termed the front of the machine, are the two angle irons 4—4, forming the longitudinal guide-way 5.

35 Slidably mounted upon said transverse bars 3—3, adjacent the rear of the machine, are similar angle bars 6—6, forming the longitudinal guide-way 7, and the bars 3—3 are provided with holes 8 for the reception of 40 pins 9 to hold the guide-way 7 in adjusted position.

Slidably mounted in the guide-way 5 is the head-block 10 provided with a threaded central opening 11, adapted to engage the 45 operating screw 12, and carrying at its inner end the flanges 13—13, adapted to engage the inner face of the angle irons 4—4 to hold the head-block against stress or pressure of the operating screw 12.

50 A similar head-block is also mounted in the longitudinal guide-way 7, within which is mounted the opposing operating screw 14.

Embracing or enclosing the head-block 10 is the loop or link 15, provided in its outer 55 end with a central opening for the loose reception of screw 12, while its inner end 16 is

solid and is engaged by the inner end of screw 12.

A duplicate loop or link 17 is similarly secured to the head-block mounted in the 60 guide-way 7 at the rear of the machine.

Rigidly secured to the posts 1—1 and beneath the angle irons 4—4 and 6—6, respectively, are oppositely disposed longitudinal bars 18 (rear bar not shown). Each of these 65 bars is provided in its upper edge with a series of notches 19, in which are mounted the transverse rods 20, which serve as adjustable supports for the wheel, in order that the latter may be held in the desired position to be 70 operated upon.

21—21 represent removable blocks, suggesting how the same may be placed between the angle irons or bars 4 and 6 and the wheel, to hold or support the latter rigidly against pressure of the operating screw. 75

In the wheel W in position, as shown in Figure 1, the solid lines of the disk 21 indicate the dents or displacements in the same, while the dotted lines indicate the correct 80 shape or outline of the disk.

In the operation of my machine, the wheel is first placed in position, as shown in Figures 1 and 2, resting upon the transverse bars 20 properly adjusted to hold the wheel 85 in the necessary position to bring the contact of the operating screw 12 and 14 (one or both) with the disk at the point of bend or displacement which it is desired to correct, after which the proper operating screw 90 (one or both) is turned sufficiently to effect such correction.

While two operating screws make the machine much more effective and satisfactory in its operation, it is obvious that it can be 95 used with only one guideway, head-block and operating screw, by providing sufficient back support for the wheel to resist the pressure of the operating screw from the front.

I claim:

1. In a device for straightening wheels, a rigid frame-work, a pair of oppositely disposed, parallel guide-ways in said frame-work, a head-block mounted in each of said guide-ways, each of said head-blocks being provided with a threaded central opening, an operating screw mounted in each of said openings and adapted to engage the wheel, and means for holding the wheel in the desired position in the frame-work. 105

2. In a device for straightening wheels, a rigid frame-work, a longitudinal guide-way 110

adjacent the front of said frame-work, a head-block slidably mounted in said guideway and provided with a threaded central opening, an operating screw mounted in said opening and adapted to engage the wheel, a longitudinal guide-way adjacent the rear of said frame-work and laterally adjustable, a head-block slidably mounted in said guide-

way and provided with a threaded central opening, an operating screw mounted in said opening and adapted to engage the wheel, and means for holding the wheel in the desired position in the frame-work. ¹⁰

In testimony whereof, I have hereunto affixed my signature.

JOHN F. WINTER.
